UNITED STATES PATENT OFFICE

ROBERT C. KAHRMANN, OF ELIZABETH, NEW JERSEY, ASSIGNOR TO AKTINSON, FENLON CO., INC., OF NEW YORK, N. Y., A CORPORATION OF NEW YORK

DESIGN FOR A TEXTILE FABRIC OR THE LIKE

Application filed June 5, 1931. Serial No. 40,094. Term of patent 7 years.

To all whom it may concern:

Be it known that I, ROBERT C. KAHRMANN, a citizen of the United States of America and a resident of the town of Elizabeth, county of Union, and State of New Jersey, have invented a new, original, and ornamental Design for a Textile Fabric or the like, of which the following is a specification, reference being had to the accompanying drawing, forming part hereof.

The figure is a drawing of a textile fabric embodying my new design.

The horizontal upper and lower edges of the drawing constitute the marginal or selvage edges of the fabric while the dot and dash vertical lines outline the recurring unit repetition over the length of the fabric.

I claim:

The ornamental design for a textile fabric or the like, as described and shown.

ROBERT C. KAHRMANN.
